ELECTRICAL STARTING MOTOR

Application filed December 22, 1927. Serial No. 241,970.

The invention relates particularly to that type of electrical starter having a pinion of relatively few teeth, which engages a ring gear of a relatively large number of teeth on the fly wheel of the engine which is to be started, and means to quickly engage the teeth for starting and quickly disengage the teeth when starting has been effected.

One of the objects of my invention is to provide a simple and efficient means of connecting and disconnecting the electric current by the mechanical action of the starter, to the end that the starter switch, which is commonly used with this type of starter, may be eliminated.

Another object of my invention is to provide a quick action shifting mechanism so that the commutator, which serves as a starting switch to complete the circuit, may be quickly and completely shifted under the brushes for starting, and quickly and completely shifted from under the brushes when starting has been effected, to the end that the burning action, commonly encountered in starting switches due to indifferent contact, may be overcome.

Still another object, in providing a quick action shifting device of this type, is to overcome the ill effects often caused when an operator pushes the pinion only part way into mesh, thereby causing undue strain on the gear teeth. This will be impossible with the present mechanism, as the pinion will always be entirely in or entirely out.

A well known and fundamental defect in the screw pinion type of starter is that, having once entered the pinion into mesh with the gear, it depends entirely upon the firing of the engine to get the pinion out of mesh, and if, after the pinion is entered, it is found that the engine will not start, it is usually necessary to disengage the pinion and gear by some manual means.

It is one of the objects of the present invention to provide a means whereby the pinion and gear may be disengaged, by the removal of the pressure from the foot pedal, whenever the engine refuses to start.

Another well known and fundamental defect in the screw pinion and most other types

of starter is that, as soon as the engine is started and running, it is necessary for the operator to quickly remove his foot from the starting pedal. Otherwise, the pinion will go forward to again engage the fly wheel gear which will then be running too fast for engagement which consequently endangers the gear teeth. In the present invention if the operator has once depressed the foot pedal to a sufficient extent, the mechanism is such as to give quick electrical contact and quick pinion engagement, then starting, then quick electrical break and pinion disengagement, and it operates in this manner regardless of whether the operator keeps the pedal depressed or not. In order to repeat the operation he must entirely remove the pressure from the foot pedal and again depress it.

An embodiment of the invention is illustrated by the following drawings wherein—

Fig. 1 is a longitudinal cross section thru the starter.

Fig. 2 is an end view of the starter showing the brushes and brush holders.

Fig. 3 is a section taken thru the brush studs on the line 3—3 Fig. 2.

Fig. 4 is a view of the pedal end, showing also the mounting flange.

Referring to the drawings, frame 6 has mounted therein six field coils 7, wound from strip stock. The starting end of each field coil is grounded by screwing it to the pole piece, as at 8, while the finishing end of each coil is fastened to a brush stud 9, the six coils being arranged in pairs, each pair having one positive coil and its adjacent negative coil fastened to a single brush stud. Thus the brush studs 9, 11 and 13 each connect to one pair, comprising a positive and negative field coil, while the three remaining brush studs 10, 12 and 14 are connected by plate 15 to the battery.

An armature core 16 is securely mounted on shaft 17 and held by nut 18. Wound in the armature core 16 is a series of conductors 19, which, in this particular case, also form the commutator. The conductors are in turn imbedded in molded insulation 20, which forms an extension to the commutator upon

which brushes 21, 22, 23, 24, 25 and 26 may rest when no electrical contact is desired.

It is to be understood that while for purposes of illustration I have herein described specific features relating to the motor elements I do not wish to be limited to the structure shown as the objects of the invention as hereinbefore set forth may be attained by employing motor elements of other structure.

In Figure 1 the starter is shown as it appears when inoperative, with the armature core 16 axially shifted to a considerable extent in relation to the pole pieces 27, 28, etc., and with the brushes 21, 24, etc., resting on the ring of molded insulation 20. Sufficient space is provided in the frame so that the armature may be shifted to a running position with the core 16 directly under the pole pieces and the commutator directly under the brushes.

Mounted on frame 6 is a hook 29 which is supported between two suitable surfaces 30 and 31, pivoted on pin 32 and held down by spring 33. Integrally cut on shaft 17 is a pinion 34 at the end of which is securely fastened a washer 35. The hook 29 engaging washer 35 keeps the gear in its inoperative position until it is desired to operate the starter when the hook is automatically raised and the mechanism caused to shift.

For ease of assembly and in order that pinion 34 may readily enter, the frame is open at its end, as at 36. Mounted in opening 36 is a flanged bearing 37 which is held in place by screws 38 and 39. Slidably mounted in flanged bearing 37 is pedal tube 40 which is held in its inoperative position by spring 41. Rotatably mounted by a pin 42 in the end of shaft 17 is spindle 43. A collar 44 backed by pin 45 forms an abutment for spring 46. The other end of spring 46 reacts against flanged collar 47. Flanged collar 47 has a tapered hole and because its flange is pushed by spring 46 against the beveled end of bearing 37, the one end of collar 47 is eccentric with spindle 43. The conical part 48 of spindle 43 serves to bring collar 47 concentric at the proper time and will then allow pedal tube 40 to telescope over flanged collar 47.

The operation of the starter is substantially as follows:

Depressing pedal tube 40 compresses pedal return spring 41. The end of pedal tube 40 engages one side of taper-holed collar 47 thereby compressing spring 46. When sufficient energy is stored in spring 46 to shift the armature, the beveled flange of collar 47 reaches and raises the beveled end of hook 29 releasing washer 35, and the shift, which meshes the gears and brings the commutator under the brushes for running contact, takes place. When the pinion has shifted to the point of full mesh, the conical part 48 of

spindle 43 has followed and centered the taper-holed collar 47, rendering spring 46 ineffective since the spring now reacts in opposite directions on different parts of the same spindle 43, its tendency to shift the armature in either direction being neutralized. A further effect of centering taper-holed collar 47 is that it may now enter pedal tube 40, so that the mechanism is now in such condition that any force tending to unmesh the pinion can do so whether the operator releases pedal 40 or not.

Now if no restraining means were supplied the relatively light spring 49 would at once return the armature to the starting point, unmeshing the gears and breaking the electrical circuit without waiting for cranking to be effected, or for the operator to release the pedal, but the teeth of pinion 34 and engine fly wheel gear 50 are cut at a slight helical angle, the angle being such that as long as cranking effort is exerted the tendency of the angular teeth is to keep the gears in mesh, but when engine firing takes place the tendency of the angular teeth is to throw the gears out of mesh. Thus it is only after engine firing has taken place that the light spring 49 is able to return the armature to the starting point.

If, however, the engine refuses to fire and cranking continues longer than desired the pedal may be released and the stronger spring 41 pulling tube 40 against shoulder 51 of spindle 43 forcibly withdraws the gears from mesh and breaks the circuit.

The starting device here shown embodies the several novel features of my invention in the form which I consider as serving the most useful purpose, but some of the combinations of elements disclosed produce equal results when applied to other devices than electrical starting motors. For instance, the quick acting mechanism shown may be applied to many purely mechanical devices, or, the quick acting means of making and breaking an electric circuit may be applied to many electrical devices. Even for starter purposes the electrical connections may be considerably modified. The commutator may have its brush track on the end thereof, or the contact members used to close the circuit may consist of members other than the commutator and brushes, and since no use is made of the solenoid action of the armature to pull it into operative position, a starting motor having an axially immovable armature, but with other axially movable parts to perform the functions set forth, is considered within the spirit of the invention.

Holding this view of the scope of the invention, I claim—

1. Engine starting apparatus comprising: a gear, secured to said engine to revolve said engine, an electric motor, a shaft for said motor axially movable therein, a pinion se-

- cured to said shaft normally out of engagement with said gear but adapted to engage said gear when moved axially by said shaft, electric circuit closing means for said motor normally open but operable to be closed by endwise movement of said shaft from its normal non-operating position, means within manual control to apply energy to urge said shaft to move axially, means to release 5 said energy to operate said shaft, and means beyond manual control after said release to operate said shaft to engage and disengage said pinion and to quickly open and close said circuit closing means.
- 10 2. In engine starting apparatus, the combination of a gear secured to said engine to revolve said engine; an electric motor; a pinion adapted to be rotated by said motor, said pinion being normally out of engagement, but axially movable to engage said gear; electric circuit closing means for said motor normally open but operable to be closed by endwise movement of said pinion into engagement; spring means to operate said pinion into and out of engagement; manual means to stress and release said spring means, said manual means being incapable 15 of restraining said spring means from operating said pinion into and out of engagement; manual means to stress and release said spring means, said manual means being incapable of restraining said spring means from operating said pinion into and out of engagement after said release has taken place.
- 20 3. Engine starting apparatus comprising, in combination, a gear secured to said engine to revolve said engine; an electric motor; a pinion adapted to be rotated by said motor, said pinion being normally out of engagement, but axially movable to engage said gear; electric circuit closing means for said motor normally open but operable to be quickly closed and again opened by movement of said pinion into and out of engagement; spring mechanism adapted to progressively operate said pinion first into and then out of engagement; manual means to energize said spring mechanism; means to restrain action of said spring mechanism until it is suitably energized; and means to release 25 said spring mechanism from operative control of said manual means until after it has operated said pinion first into and then out of engagement, the angle of the helical teeth of the gear and pinion being such as will produce an axial thrust tending to hold said pinion in engagement until the engine starts and to disengage said pinion after the engine is started.
- 30 4. The combination, in engine starting apparatus, of a gear secured to said engine to revolve said engine; an electric motor; a pinion adapted to be rotated by said motor, said pinion being normally out of engagement, but axially movable to engage said gear; electric circuit closing means for said motor, normally open but operable to be closed and again opened by movement of said pinion into and out of engagement; spring mechanism adapted to progressively operate said pinion first into and then out of engagement; manual means to energize said spring mechanism; means to restrain action of said spring mechanism until it is suitably energized; 35 and means to release said spring mechanism from operative control of said manual means until after it has operated said pinion first into and then out of engagement.
- 40 5. The combination, in engine starting apparatus, of a gear secured to said engine to revolve said engine; an electric motor; a pinion adapted to be rotated by said motor, said pinion being normally out of engagement, but axially movable to engage said gear; electric circuit closing means for said motor, normally open but operable to be closed and again opened by movement of said pinion into and out of engagement; spring mechanism adapted to progressively operate said pinion first into and then out of engagement; manual means to energize said spring mechanism; means to restrain action of said spring mechanism until it is suitably energized; and means to release 45 said spring mechanism from operative control of said manual means until after it has operated said pinion first into and then out of engagement.
- 50 6. In an engine starter, the combination of a gear secured to said engine to revolve said engine; an electric motor; a pinion adapted to be rotated by said motor, said pinion being normally out of engagement but axially movable to engage said gear; electric circuit closing means for said motor, normally open but operable to be closed and again opened by movement of said pinion into and out of engagement; a relatively strong spring; a relatively weak spring; manual means to appropriately stress said relatively strong spring; means to restrain said relatively strong spring until it is appropriately stressed; and means to release 55 said restraining means, said springs being so placed that release of said relatively strong spring moves said pinion axially into engagement, closes said circuit closing means, and stresses said relatively weak spring, and the return to normal of said relatively weak spring removes said pinion from engagement and opens said circuit closing means.
- 60 7. In an engine starter, the combination of a gear secured to said engine to revolve said engine; an electric motor; a pinion adapted to be rotated by said motor, said pinion being normally out of engagement but axially movable to engage said gear; electric circuit closing means for said motor, normally open but adapted to be closed and again opened by movement of said pinion into and out of en- 65

gagement; a relatively strong spring; a relatively weak spring; manual means to appropriately compress said relatively strong spring; means to restrain said relatively strong spring until it is appropriately compressed; and means to suddenly release said restraining means, said springs being so placed that expansion of said relatively strong spring moves said pinion axially into engagement closes said circuit closing means, and compresses said relatively weak spring, and expansion of said relatively weak spring removes said pinion from engagement and opens said circuit closing means.

15. 8. In engine starting apparatus, the combination of a helical toothed gear secured to said engine to revolve said engine; an electric motor; a helical toothed pinion adapted to be rotated by said motor, said pinion being normally out of engagement but axially movable to engage said gear; electric circuit closing means for said motor, normally open but adapted to be closed and again opened by movement of said pinion into and out of engagement; a relatively strong spring; a relatively weak spring; manual means to appropriately stress said relatively strong spring; means to restrain said relatively strong spring until it is appropriately stressed; and means to release said restraining means, said springs being so placed that release of said relatively strong spring moves said pinion axially into engagement, closes said circuit closing means, and stresses said relatively weak spring, and the return to normal of said relatively weak spring removes said pinion from engagement and opens said circuit closing means, and the teeth of said helical gear and pinion being at such an angle as will produce an axial thrust adapted to prevent said relatively weak spring from returning to normal as long as said motor is turning said engine and to assist said relatively weak spring in returning to normal when said engine turns said motor.

9. In engine starting apparatus, the combination of a gear secured to said engine to revolve said engine; an electric motor; a pinion adapted to be rotated by said motor, said pinion being normally out of engagement but axially movable to engage said gear; electric circuit closing means for said motor normally open but adapted to be closed and again opened by movement of said pinion into and out of engagement; a relatively weak spring adapted to keep said pinion out of engagement; a relatively strong spring normally unstressed but adapted to be placed in stress against said pinion to engage said pinion; manually operable means to stress said strong spring; means to restrain movement of said pinion into engagement until said strong spring is suitably stressed; means to release said restraining means; and means operable by movement of said pinion into en-

gagement to release said strong spring from the control of said manual means.

In testimony whereof I hereunto set my hand.

VINCENT G. APPLE.
